OSCAR L. COFFEY, OF HARVEY, ILLINOIS, ASSIGNOR TO WHITING CORPORATION, OF HARVEY, ILLINOIS A CORPORATION OF ILLINOIS.

DROP-PIT MECHANISM.

Application filed October 1, 1928. Serial No. 309,386.

- The invention relates to drop pit mechanism of the type used for removing heavy wheels from railroad locomotives or other vehicles.
- The objects of the invention are to provide improved controlling mechanism in drop pits of the type in which an electric motor is used for driving the gearing which is employed to lift and lower the drop table; improved controlling mechanism by which the table will be operated at differential speeds, namely, at low speed during the range of the table in which the vehicle wheels are lifted above track level to permit disconnection of the wheel axles from the vehicle and the connection thereof to the vehicle, and at high speed during the remainder of the range of movement of the table; improved controlling mechanism by which this speed change will be automatically effected as the lifting mechanism passes from one of said ranges to the other; improved controlling mechanism which renders the lifting mechanism inoperative when the table locking devices are not properly set; improved controlling mechanism which will automatically stop the lifting mechanism when the table reaches its high limit of travel; improved high limit controlling mechanism which is controlled by the relative position of the lifting carriage or table thereon relatively to the trolley in the pit; and improved controlling mechanism for controlling the low limit of the lifting mechanism.
- The invention consists in the several novel features hereinafter set forth and more particularly defined by claims at the conclusion hereof.
- In the drawings: Fig. 1 is a side elevation of mechanism embodying the invention. Fig. 1^a is an inverted plan of the speed change and high limit switches and the device for operating them. Fig. 2 is a plan of the trolley and the lifting mechanism thereon. Fig. 3 is an end elevation, parts being shown in section. Figs. 4 and 5 are details of one of the automatically operated switches. Fig. 6 is a section through the drop table on line 6-6 of Fig. 3. Fig. 7 is a diagram of the electric controlling means and circuit connections for the motor which operates the mechanism.
- The invention is exemplified with an equipment comprising a track 8 interrupted at the margins of a transverse pit 9, rails 10 on the
- bottom of the pit, a drop table H provided with rail sections 12 to bridge the pit between the rails of track 8; and locking bolts 13, whereby the table may be locked in track-bridging position. The table is composed of pairs of longitudinal girders 11^a underlying the rail sections 12, outside longitudinal girders 11^b, and cross girders 11^c rigidly secured to said longitudinal girders to form a rigid supporting structure for rail sections 12. Side platforms 11^d are supported on the longitudinal girders 11^a and 11^b. Bolts 13 are operable into recesses 13^e to stationarily support the table. There are four of said bolts underlying the ends of the rail sections 12 respectively, and guided in blocks 13^f fixed between girders 11^a. These bolts are conjointly operable by a lever 13^g which is fixed to a shaft 13^h which is journaled in bearings carried by the table, rocker levers 13ⁱ, and links 13^j between said levers and bolts 13 respectively. The mechanism for raising and lowering the table H, so that a wheel or load may be lowered into the pit for transfer to another track 8 and raised to the desired height, is mounted on a trolley or wheeled truck I. This trolley comprises a frame composed of longitudinal girders 14^a and cross girders 14^b, and is provided with wheels 14^c mounted in bearings connected to said longitudinal girders, and adapted to run on rails 10. Suitable mechanism is provided for propelling the trolley as well understood in the art.
- The lifting mechanism comprises four standards 15 having their lower ends rigidly secured in blocks 15^a secured to the girders 14^a of the trolley, and worm gears 16 threaded to standards 15 and adapted, by their rotation in opposite directions, to raise and lower a carriage G which is adapted to separably engage the table H, so that the carriage may be raised and lowered independently of the table when desired. The frame of this carriage comprises a pair of girders 17^a at each end of the carriage, girders 17^b secured to the inner girders 17^a, and sectional gear cases 17^c secured to girders 17^a. Said gear cases contain the gears 16, and worms 26, and are adapted to contain lubricant for said wheels 14^c and the screw-threads on standards 15. An electric motor B is mounted on a frame member 19^a fixed to the inner girders 17^a. Gearing driven by said motor for simultaneously rotating worm gears 16 comprises a pinion 20

on the motor shaft, a gear 21 meshing with said pinion and fixed to a shaft 22 which is mounted in bearings on the carriage G, bevelled pinions 23 on the ends of shaft 22, bevelled gears 24 meshing with gears 23 and fixed to shafts 25 respectively, and worm wheels 26 on the ends of shafts 25 respectively engaging the worm gears 16. When the motor B is operated in one direction, it will, through the described gearing, simultaneously rotate the worm gears 16 to raise the carriage G, and when the motor is operated in reverse direction, it will rotate gears 16 to lower the carriage G. This exemplifies lifting mechanism for a drop table which is driven by a motor and gearing mounted on a lifting carriage which separably engages the drop table.

The mechanism for controlling the operation of the electric motor B, which is mounted on a carriage G, to raise or lower the drop table H, and the carriage independently of the table, comprises a manually operable switch-device A which comprises a normally open switch-button 40 and contact 41, for controlling the circuit for the lowering movement of the carriage, a normally closed stop-button 44, and a contact 45, and a normally open switch button 43 with a contact 42 for controlling the lifting circuit; a normally closed switch C which includes a spring-pressed arm c' and a contact c² engageable by said spring-pressed roller carrying arm, for automatically opening the lifting control circuit when the carriage has reached its predetermined high limit, controlled by a connection between the carriage G and the trolley I; a spring-closed switch D, controlled by the locking mechanism for the drop table, which will open the lowering-control circuit when the table-latches 13 are out of either their fully closed or open positions, and includes a spring-pressed arm d' and a contact d² engageable by the arm; a spring-closed switch E, for controlling the low limit of the movement of the carriage G, which includes a spring-pressed arm e' and a contact e² separable from said contact to open the lowering control circuit when the carriage reaches its low predetermined limit; and a speed-control switch F, controlled by the movement of the carriage, to control the operation of the motor B so the lifting mechanism will be operated at a relatively slow speed within a predetermined range, while the table is near its track-bridging position and at a higher speed during the remainder of the lifting and lowering movements of the carriage. Each of the switches C, D, E and F are substantially of the construction shown in Figs. 4 and 5. Each is enclosed in a box 30, and comprises a shaft 31, pivoted in the box, and to which a switch-arm is secured, a bridge-pin 32 on the arm, to engage a pair of spring contacts, a spring 33 for normally shifting the arm to

close a circuit at said contacts, a roller 34 adapted to be engaged by the operating element, and a stop 35 to position the arm when the switch is closed.

This controlling mechanism also comprises an electro-magnet which includes a helix c³ for operating a pair of connected switch-members 59, 60, which are insulated from each other, and a bridging member 61, to control the motor circuit for lifting the carriage, an electro-magnet which comprises a helix e³ for shifting a pair of switch-members 62, 63, and a bridge contact 64, to control the motor circuit for the lowering movement of the carriage, an electro-magnet comprising a helix 58 for operating a pair of switch-members 71, 72 for controlling a control circuit for operating the motor to drive the lifting mechanism at high speed; an electro-magnet comprising a helix 57 for operating a pair of switch-members 75, 76, for controlling the motor-circuit to operate the motor B at low speed; and a relay-magnet, controlled by the speed-control switch F, and including a helix f³ for operating a pair of switch-members 79, 80, and a bridge-member 81. All of said magnets and switches are contained in a box 36 secured to the carriage G.

The motor B is of the two speed, reversible type with separate windings for the two speeds at which it is desired to operate the gearing, in either direction. Current for the operation of motor B, which is vertically movable with the carriage G and the controlling circuits, is supplied by line conductors 50, 51 and 52. The switch-device A is usually suspended from the box 36 by a flexible cord 37. The lift-control switch C is operated by a cam 90 on an arm 91 which is fixed to a shaft 92 journaled in brackets 93 fixed to the girders 17^a of the carriage G (Fig. 1^a). The switch C is normally closed, and the cam 90 engages the switch arm c' to separate it from contact c² to open the circuit and cause the motor to stop when the carriage has been raised to its high predetermined limit. Arm 91 is adjustably secured to shaft 92 so the limit may be varied as desired. The speed-control switch F is operated by a cam 94 on an arm 95 which is also adjustably fixed to the shaft 92, so the point at which the speed change is effected may be varied as desired. Normally, switch F is closed to close the circuit for controlling the motor B at high speed. When cam 94 engages arm f' of said switch, it will separate said arm from the contact f² to open the high speed control circuit and cause a circuit to be established which will cause the motor to drive the lifting mechanism at low speed. The boxes containing the switches C and F are fixed to a bar 37 secured to girders 17^a of the carriage G. Shaft 92, which operates arms 91 and 95, is rocked by a linkage which comprises a pair of links 96 and 97 between the frame of trolley I and the

carriage G. Link 96 has its upper end fixed to shaft 92 and its lower end pivoted at 98 to the upper end of link 97, and the latter has its lower end pivoted, at 99, to lugs 100 which are fixed to the trolley I. The lock-controlled switch D is normally closed and operated by a cam 101 on an arm 102 which is fixed to the cross-shaft 13* which controls the positions and movements of the locking bolts 13 for the table H. Cam 101 is positioned to swing across the path of the roller on the end of arm d' as the bolts 13 are shifted between their locking and unlocked positions, and to pass out of engagement with said roller when the bolts are either in their fully extended or fully retracted positions. The box containing switch D is fixed to an angle-lug 38 which is fixed to a girder 17* of carriage G. The low limit switch E is mounted on the carriage G, and the roller on its arm e' is adapted to strike an angle iron lug 106 which is fixed to the trolley-frame, so that the switch will be operated only when the carriage reaches the lower limit of its movement.

The operation will be as follows: Assuming the table H to be in track-bridging position shown in Fig. 3, and the bolts 13 fully retracted, the switch F will be open, because at such time the cam 94 will be positioned to separate arm f' from contact f². In unwheeling a locomotive, usually, the first step is to lift the table H sufficiently to raise a pair of the locomotive wheels to permit them to be disconnected from the locomotive. For this purpose, the operator will press the lift-control button 43 of the manually controlled switch-device A, so it will engage contact 42, whereupon the following circuit for controlling the operation of the motor B at low speed will be established: line conductor 51, conductor 107, arm c' and contact c² of the lift-control switch C, conductor 108, helix e³, conductor 109, contact 42, switch-member 43, conductors 110, 111, conductor 116, and line-conductor 52. This will energize the helix e³ of the lift-control magnet, and operate switch members 59 and 60 to close against contacts 53, 65 respectively, and bridge-member 61 to engage contacts 66, 67, and thereupon the following circuit will be established through the helix 57 of the low-speed control magnet; viz line conductor 51, contact 53, switch-member 59, conductor 113, contact 83, bridge-member 81, contact 82, conductor 114, helix 57, conductor 115, conductor 119, switch-member 60, contact 65, conductor 116, and line conductor 52. The energizing of helix 57 will establish the following circuit for the operation of the motor B at low speed; viz line conductor 51, conductor 107, contact 53, switch-member 59, conductor 113, contact 77, switch-member 75, conductor 117, the low-speed winding of motor B, conductor 118, switch-member 76, contact 78, conductors 115, 119, switch-member 60, contact 65, conductor 116, and line conductor 52. The line conductor 50 leads to the motor B, as well understood in the art. This will cause the motor B to operate in one direction and operate the lifting mechanism at low speed until the high-limit switch C is opened, and when the latter occurs, the circuit through helix e³ will be opened, to release switch-members 59, 60, and open the motor circuit last described at contacts 53, 65, to stop the operation of the motor.

When the wheels have been uncoupled from the locomotive, the operator will press switch-button 40 of device A, so it will engage contact 41, whereupon the following control circuit for lowering the table at low speed will be established; viz line conductor 51, conductor 107, switch-arm c' (then separated from contact c²) of switch C, conductor 56, switch-arm d', and contact d² of the lock-controlled switch D, conductor 120, contact e², and arm e' of the switch E, conductor 121, helix e³, conductor 122, contact 41, switch-button 40 of device A, conductor 111, and line conductor 52. This will energize helix e³ to shift switch-members 62, 63, and 64, to close the following control circuit; viz line conductor 51, conductor 107, contact 54, switch-member 62, conductor 119, conductor 115, helix 57, conductor 114, contact 82, bridge-member 81, contact 83, conductor 113, switch-member 63, contact 68, conductor 116, and line conductor 52. When the helix 57 is energized, the following circuit will be established for the operation of the motor; line-conductor 51, conductor 107, contact 54, switch-member 62, conductors 119, 115, contact 78, switch-member 76, conductor 118, the low-speed reverse winding of motor B, conductor 117, switch-member 75, contact 77, conductor 113, switch-member 63, contact 68, conductor 116, and line conductor 52. The motor will then lower the carriage and drop-table at low speed until the cam 94, which controls the switch F, releases arm f' of said switch after the carriage has been lowered at slow speed the range desired, usually from six to twelve inches. This permits accurate operation of the table H into the desired positions while the wheel-locking wedges are being removed. Switch-buttons 40, and 43 are of the spring-pressed, normally open type, so that when the operator releases either of the coacting members, the circuits controlled thereby will be opened. During these cycles, the operator must hold his finger on one of the push buttons to continue the lifting or lowering operation, and the lifting mechanism will automatically stop when the push button is released by the operator. Assuming that it is desired to continue the lowering movement, the operator will continue to keep his finger on push button 40 to close it against contact 41, and when the cam 94 releases the switch-arm f', as the result of

the lowering of the carriage G, the following control circuit will be established through helix f^3 for causing the motor B to operate in lowering direction and at high speed at all times when switch F is closed, which circuit is as follows: line conductor 51, conductor 107, conductor 124, helix f^3 , conductor 125, contact f^2 , arm f' , conductor 116, and line-conductor 52. When the helix f^3 is energized, it will shift switch-members 79, 80, and 81, to interrupt the circuit at switch-member 81, and contacts 82 and 83, and establish the following circuit: line conductor 51, conductor 107, switch-arm c' , conductor 56, switch-arm d' , contact d^2 , conductor 120, contact e^2 , arm e' , conductor 121, helix e^3 of the lowering control magnet, conductor 122, contact 41, push-button 40, conductor 111, and line conductor 52. This circuit will cause helix e^3 to be energized which will shift bridge-member 64 into engagement with contacts 69, 70, to establish a circuit which will make it possible to continue the lowering operation without the necessity of the operator keeping his finger on the button 40. The circuit for this purpose will be as follows: line conductor 51, conductor 107, arm c' , conductor 56, arm d' , contact d^2 , conductor 120, contact e^2 , arm e' , conductor 121, helix e^3 , conductor 122, contact 69, bridge-member 64, contact 70, conductor 126, contact 85, switch-member 80, conductor 127, push-button 44, and contact 45, which are normally closed, conductor 111 and line conductor 52. The energizing of helix e^3 will also close the following circuit to energize helix 58 of the high speed lowering control magnet; viz line conductor 51, conductor 107, contact 54, switch-member 62, conductors 119, 115, helix 58, conductor 129, contact 84, switch-member 79, conductor 113, switch-member 63, contact 68, conductor 116, and line conductor 52. When helix 58 is energized, switch members 71, 72 will be shifted to close the following circuit for the high speed operation of motor B during the remainder of the lowering cycle; viz line conductor 51, conductor 107, contact 54, switch-member 62, conductors 119, 115, contact 74, switch-member 72, conductor 130, the high speed winding of motor B, conductor 131, switch-member 71, contact 73, conductor 113, switch-member 63, contact 68, conductor 116, and line conductor 52. The motor B will thereupon lower the carriage G either until the operator presses the push button 44 to stop the motor, or until the switch E is opened as the carriage reaches its low limit. When the carriage G, with the table thereon, has been lowered, and it is desired to raise the table with the load thereon, to the track level, the operator will press button 43, so it will engage contact 42, which will establish the following circuit: line conductor 51, conductor 107, switch arm c' , contact c^2 , conductor 108, helix c^3 , conductor 109, contact 42, push-button 43, conductors 110, 111, and line conductor 52. Simultaneously, a parallel circuit will be established, so that the operation of the motor B may be continued without holding push button 43 closed, which will be as follows: line conductor 51, conductor 107, arm c' , contact c^2 , conductor 108, helix c^3 , conductor 109, contact 66, bridge-member 61, contact 67, conductor 126, contact 85, switch-member 80, conductor 127, push button 44, contact 45, conductor 111, and line conductor 52. When helix c^3 is thus energized, it will also establish a circuit for energizing the helix 58 of the high speed lift control magnet, to close a circuit for causing the motor to lift the carriage which circuit will be as follows: line conductor 51, conductor 107, contact 53, switch member 59, conductor 113, switch-member 79, contact 84, conductor 129, helix 58, conductors 115, 119, switch-member 60, contact 65, and conductors 116, 52. Helix 58 will then shift switch-members 71, 72 to establish the circuit through the motor B to operate the gearing in the proper direction to lift the carriage, which will be as follows: conductors 51, 107, contact 53, switch-member 59, conductor 113, contact 73, switch member 71, conductor 131, the winding of motor B, conductor 130, switch member 72, contact 74, conductors 115, 119, switch member 60, contact 65, and conductors 116, 52. This circuit will remain closed until the operator presses the stop button 44, or if the carriage is to be lifted above the commencement of the range of low speed movement, until the switch F is opened by the cam 94, which is operated by the linkage 96, 97, to cause the additional upper travel of the carriage to be effected at low speed. When the switch F has been opened, helix f^3 will be deenergized to permit switch members 79, 80 to separate from contacts 84, 85, so that the same control circuit will be established as described in connection with the initial low speed lifting operation, which circuit will be maintained until the switch C is opened by the cam 90.

In practice, it is desirable to have the bolts 13 fully extended to insure the proper supporting of the table to prevent the bolts from becoming accidentally released as might occur if they are not fully extended. For this purpose, the switch D is provided so that if the bolts 13 are in any intermediate position, cam 101 will shift switch-arm d' to open the circuit at contact d^2 , and thus interrupt the control circuit to prevent the operation of the motor B in lowering direction until the bolts have been properly set. The opening of the circuit at contact d^2 interrupts the circuit through helix e^3 so that the motor circuit will be interrupted at contacts 54 and 68.

The invention exemplifies controlling mechanism for a drop-table which is operated by a motor on the lifting carriage, in which provi-

- sion is made for lifting and lowering the table at different speeds, so that the table may be accurately positioned within that range of its travel in which the wheels are separated and attached to the vehicle or locomotive; in which provision is made for automatically stopping the motor when the table reaches its high limit; in which the motor is automatically stopped when the table reaches its low limit of travel; in which the motor is automatically stopped or rendered inoperative to lower the table, if the locking mechanism is not properly set; and in which the manual control device is such as to permit the operation of the motor during the high speed cycles without the necessity of the operator holding the switch in position; and in which the movements of the speed-control and high-limit switches are controlled by a connection between the lifting carriage and the trolley.
- The invention is not to be understood as restricted to the details set forth, since these may be modified within the scope of the appended claims, without departing from the spirit and scope of the invention.
- Having thus described the invention, what I claim as new and desire to secure by Letters Patent, is:
1. In mechanism of the class described, the combination with a pit, and a drop-table adapted to move vertically in the pit, of lifting mechanism mounted to travel laterally in the pit for shifting the table, an electric motor for driving said mechanism, and means for controlling the motor to operate the lifting mechanism at different speeds during different ranges of travel.
  2. In mechanism of the class described, the combination with a pit, and a drop-table adapted to move vertically in the pit, of lifting mechanism mounted to travel laterally in the pit for shifting the table, an electric motor for driving said mechanism, and means for controlling the motor to operate the lifting mechanism to raise and lower the table at different speeds during different ranges of travel.
  3. In mechanism of the class described, the combination with a pit, and a drop-table adapted to move vertically in the pit, of lifting mechanism mounted to travel laterally in the pit for shifting the table, a reversible electric motor for driving said mechanism, and means for controlling the motor to operate the lifting mechanism to raise and lower the table at different speeds during different ranges of travel.
  4. In mechanism of the class described, the combination with a pit, and a drop-table adapted to move vertically in the pit, lifting mechanism mounted to travel laterally in the pit for shifting the table, comprising screws, elements on the screws, and an electric motor for driving said elements, and means for controlling the motor to operate said elements at different speeds during different ranges of travel.
  5. In mechanism of the class described, the combination with a pit and a drop-table adapted to move vertically in the pit, lifting mechanism mounted to travel laterally in the pit for shifting the table, comprising screws, elements on the screws and an electric motor for driving said elements, and means for controlling the motor to operate said elements to raise and lower the table at different speeds during different ranges of travel.
  6. In mechanism of the class described, the combination with a pit, and a drop-table adapted to move vertically in the pit, of a trolley mounted to travel laterally in the pit, lifting mechanism on the trolley, for shifting the table, comprising an electric motor, and means for controlling the motor to operate the lifting mechanism at different speeds during different ranges of travel.
  7. In mechanism of the class described, the combination with a pit and a drop-table adapted to move vertically in the pit, of a trolley mounted to travel laterally in the pit, lifting mechanism on the trolley, for shifting the table, comprising an electric motor, and means for controlling the motor to operate the lifting mechanism at different speeds to raise and lower the table, during different ranges of its travel.
  8. In mechanism of the class described, the combination with a pit, and a drop-table adapted to move vertically in the pit, of lifting mechanism mounted to travel laterally in the pit for shifting the table comprising an electric motor, and means for controlling the motor to operate the lifting mechanism at different speeds, comprising a speed-changing switch, controlled by the position of the lifting mechanism.
  9. In mechanism of the class described, the combination with a pit, and a drop-table adapted to move vertically in the pit, of a trolley mounted to travel laterally in the pit, lifting mechanism on the trolley, for shifting the table, comprising an electric motor, and means carried on the trolley, for controlling the motor to operate the lifting mechanism at different speeds, comprising a speed changing switch and a connection between the lifting mechanism and the trolley.
  10. In mechanism of the class described, the combination with a pit, and a drop-table adapted to move vertically in the pit, of lifting mechanism mounted to travel laterally in the pit for shifting the table, an electric motor for driving said mechanism, and means for controlling the motor to operate the lifting mechanism at different speeds during different ranges of travel, and to automatically stop the motor when the lifting mechanism reaches a predetermined height.
  11. In mechanism of the class described,

- the combination with a pit, and a drop-table adapted to move vertically in the pit, of lifting mechanism mounted to travel laterally in the pit for shifting the table, an electric motor for driving said mechanism, and means for controlling the motor to operate the lifting mechanism at different speeds during different ranges of travel, and to automatically stop the motor at predetermined high and low limits.
12. In mechanism of the class described, the combination with a pit, and a drop-table adapted to move vertically in the pit, lifting mechanism mounted to travel laterally in the pit for shifting the table, comprising screws, elements on the screws, and an electric motor for driving said elements, and means for controlling the motor to operate said elements at different speeds during different ranges of travel, and to automatically stop the motor when the lifting mechanism reaches a predetermined limit.
13. In mechanism of the class described, the combination with a pit, and a drop-table adapted to move vertically in the pit, of a trolley mounted to travel laterally in the pit, lifting mechanism on the trolley, for shifting the table, comprising an electric motor, and means carried on the trolley, for controlling the motor to operate the lifting mechanism at different speeds during different ranges of its travel, and to automatically stop the motor when the lifting mechanism reaches a predetermined high limit.
14. In mechanism of the class described, the combination with a pit and a drop table adapted to move vertically in the pit, of lifting mechanism mounted to travel laterally in the pit for shifting the table, comprising an electric motor, and means for controlling the motor to operate the lifting mechanism at low speed during a predetermined upper range of travel of the table and at a higher speed during its lower range of travel.
15. In mechanism of the class described, the combination with a pit, and a drop-table adapted to move vertically in the pit, of lifting mechanism mounted to travel laterally in the pit for shifting the table, an electric motor for driving said mechanism, and means for controlling the motor to operate the lifting mechanism automatically at different speeds during different ranges of travel, and to automatically stop the motor when the lifting mechanism reaches a predetermined height.
16. In mechanism of the class described, the combination with a pit and a drop table adapted to move vertically in the pit, of a trolley mounted to travel laterally in the pit, lifting mechanism on the trolley for shifting the table, comprising an electric motor, and means carried on the trolley, for automatically controlling the motor to operate the lifting mechanism at low speed during a predetermined upper range of travel of the table and at a higher speed during its lower range of travel.
17. In mechanism of the class described, the combination with a pit and a drop-table adapted to move vertically in the pit, of lifting mechanism mounted to travel laterally in the pit for shifting the table comprising an electric motor, and means for automatically controlling the motor to operate the lifting mechanism at low speed during a predetermined upper range of travel of the table and at a higher speed during its lower range of travel.
18. In mechanism of the class described, the combination with a pit and a drop-table adapted to move vertically in the pit, of lifting mechanism mounted to travel laterally in the pit for shifting the table, comprising a reversible electric motor, and means for controlling the motor to operate the lifting mechanism at low speed during a predetermined upper range of the table and at a higher speed during the lower range of movement of the table, comprising a high-speed control magnet and a low speed control magnet.
19. In mechanism of the class described, the combination with a pit and a drop-table adapted to move vertically in the pit, of lifting mechanism mounted to travel laterally in the pit for shifting the table, comprising a reversible electric motor, and means for controlling the motor to operate the lifting mechanism at low speed during a predetermined upper range of the table and at a higher speed during the lower range of movement of the table, comprising a high-speed control magnet, a low speed control magnet, and magnets for controlling the direction of operation of the motor.
20. In mechanism of the class described, the combination with a pit and a drop-table adapted to move vertically in the pit, of lifting mechanism mounted to travel laterally in the pit for shifting the table, comprising an electric motor, and a carriage adapted to separably engage the table, switch-means mounted on the carriage for controlling the motor to operate at different speeds during different ranges of travel of the lifting mechanism, and a connection for shifting said controlling means, operated by the vertical movement of the carriage.
21. In mechanism of the class described, the combination with a pit and a drop table adapted to move vertically in the pit, of lifting mechanism for shifting the table, comprising an electric motor, and a carriage adapted to separably engage the table, switch-means for controlling the motor to operate at different speeds during different ranges of travel of the lifting mechanism, and

a pair of links operated by the vertical movement of the carriage, for operating said switch-means.

22. In mechanism of the class described, the combination with a pit and a drop table adapted to move vertically in the pit, of a trolley mounted to travel laterally in the pit, lifting mechanism on the trolley, for shifting the table comprising an electric motor and a carriage adapted to separably engage the table, a switch for controlling the motor to operate at different speeds, during different ranges of its travel, comprising a switch mounted on the carriage, and a connection between the carriage and the trolley for controlling said switch.

23. In mechanism of the class described, the combination with a pit and a drop table adapted to move vertically in the pit, of a trolley, lifting mechanism on the trolley, for shifting the table comprising an electric motor and a carriage adapted to separably engage the table, a switch for controlling the motor to operate at different speeds during different ranges of its travel, comprising a switch mounted on the carriage, and a link-connection between the carriage and the trolley for controlling said switch.

24. In mechanism of the class described, the combination with a pit and a drop-table adapted to move vertically in the pit, of a trolley mounted to travel laterally in the pit, lifting mechanism on the trolley for shifting the table comprising a two-speed electric motor and a carriage adapted to separably engage the table, and means for automatically controlling the motor to operate at different speeds during different ranges of its travel, comprising a switch, a connection between the carriage and the trolley for shifting said switch, and high and low speed relays controlled by said switch.

25. In mechanism of the class described, the combination with a pit and a drop-table adapted to move vertically in the pit, of a trolley mounted to travel laterally in the pit, lifting mechanism on the trolley for shifting the table comprising a reversible two-speed electric motor and a carriage adapted to separably engage the table, and means for controlling the motor to operate at different speeds during different ranges of travel, comprising a switch, a connection between the carriage and the trolley for shifting said switch, high and low speed relays, and relays for controlling the direction of rotation of the motor.

26. In mechanism of the class described, the combination with a pit and a drop-table adapted to move vertically in the pit, of lifting mechanism mounted to travel laterally in the pit for shifting the table, comprising an electric motor, means for locking the table in its raised position, and means for controlling

the operation of the motor, comprising a 65 switch, controlled by said locking means.

27. In mechanism of the class described, the combination with a pit and a drop-table adapted to move vertically in the pit, of a trolley mounted to travel laterally in the pit, 70 lifting mechanism for shifting the table, comprising an electric motor, means for locking the table in its raised position, and means for controlling the operation of the motor, comprising a switch controlled by said locking 75 means, and a device mounted on the table for controlling said switch.

28. In mechanism of the class described, the combination with a pit and a drop-table adapted to move vertically in the pit, of lifting mechanism mounted to travel laterally in the pit for shifting the table, comprising an electric motor, means for locking the table in its raised position, means for controlling the operation of the motor, and means, controlled 80 by said locking means, for rendering the motor inoperative, comprising a switch on the lifting mechanism, and means on the table to control the switch.

29. In mechanism of the class described, 90 the combination with a pit and a drop-table adapted to move vertically in the pit, of a trolley mounted to travel laterally in the pit, lifting mechanism on the trolley for shifting the table, comprising a carriage separably engaging the table, and an electric motor on the carriage, means carried by the table for locking it in its raised position, means for controlling the operation of the motor, and means, controlled by said locking means, for 95 rendering the motor inoperative, comprising a switch mounted on the carriage and a device on the table, for shifting the switch.

30. In mechanism of the class described, the combination with a pit and a drop-table 105 adapted to move vertically in the pit, of a trolley mounted to travel laterally in the pit, lifting mechanism on the trolley, for shifting the table, comprising an electric motor and a carriage separably engaging said table, 110 and on which the table is mounted, controlling means for the motor for rendering the motor inoperative when the carriage reaches its high limit comprising a switch on the carriage and a connection between the carriage and the trolley for operating said switch.

31. In mechanism of the class described, the combination with a pit and a drop-table adapted to move vertically in the pit, of a trolley mounted to travel laterally in the pit, lifting mechanism on the trolley, for shifting the table, comprising an electric motor and a carriage separably engaging said table and on which the table is mounted, controlling means for the motor, and means for rendering the motor inoperative when the carriage reaches its high limit comprising a switch on 120 125

the carriage and a link connection between the carriage and the trolley for operating said switch.

32. In mechanism of the class described, the combination with a pit and a drop-table adapted to move vertically in the pit, of a trolley mounted to travel laterally in the pit, lifting mechanism on the trolley, for shifting the table, comprising a two speed electric motor, and a carriage separably engaging said table, means for controlling the motor, automatic means for rendering the motor inoperative when the carriage reaches its high limit, comprising a switch on the carriage, a speed-control switch mounted on the carriage, and a connection between the carriage and the trolley for controlling said switches.

33. In mechanism of the class described, the combination with a pit and a drop-table adapted to move vertically in the pit, of a trolley mounted to travel laterally in the pit, lifting mechanism on the trolley, for shifting the table, comprising a two-speed electric motor, and a carriage separably engaging said table, means for controlling the motor, automatic means for rendering the motor inoperative when the carriage reaches its high limit, comprising a switch on the carriage, a speed-control switch mounted on the carriage, and a link connection between the carriage and the trolley for controlling said switches.

34. In mechanism of the class described, the combination with a pit and a drop-table adapted to move vertically in the pit, of a trolley mounted to travel laterally in the pit, lifting mechanism on the trolley for shifting the table, comprising an electric motor and a carriage separably engaging said table, and motor-controlling means comprising a switch on the carriage for rendering the motor inoperative when the carriage reaches its high limit, a shaft on the carriage for controlling the switch, and a connection between the carriage and the trolley for operating said shaft.

35. In mechanism of the class described,

the combination with a pit and a drop-table adapted to move vertically in the pit, of a trolley, lifting mechanism on the trolley, for shifting the table, comprising an electric motor and a carriage separably engaging said table, and motor controlling means comprising a switch on the carriage for rendering the motor inoperative when the carriage reaches its high limit, a shaft on the carriage for controlling the switch, and a link connection between the carriage and the trolley for operating said shaft.

36. In mechanism of the class described, the combination with a pit, and a drop-table adapted to move vertically in the pit, of lifting mechanism mounted to travel laterally in the pit for shifting the table, comprising an electric motor, and means for controlling the operation of the motor comprising a manually operable device, including open switches for controlling the up and down movements of the lifting mechanism, and a stop-switch, and means for continuing the operation of the motor independently of the raising and lowering switches, under control of the stop switch.

37. In mechanism of the class described, the combination with a pit, and a drop table adapted to move vertically in the pit, of a trolley mounted to travel laterally in the pit, lifting mechanism on the trolley for shifting the table, comprising a reversible electric motor, and means for controlling the operation of the motor, comprising a manually operable device, including normally open switches, for controlling the up and down movements of the lifting mechanism, and a stop-switch, and means for continuing the operation of the motor in either direction, independently of the raising and lowering switches, under control of the stop-switch.

Signed at Chicago, Illinois, this 28th day of September, 1928.
